BOOT

Otis G. Murty, Riverdale, Md., assignor to the
United States of America as represented by
the Secretary of the Army

Application April 3, 1953, Serial No. 24,334

Term of patent 14 years

(Cl. D7—4)

(Granted under Title 35, U. S. Code (1952),
sec. 266)

To all whom it may concern:

The design described herein, if patented, may be manufactured and used by or for the Government for governmental purposes, without the payment to me of any royalty thereon.

Be it known that I, Otis G. Murty, a citizen of the United States, residing at Riverdale, in the county of Prince Georges and State of Maryland, have invented a new, original, and ornamental Design for a Boot, of which the following is a specification, reference being had to the accompanying drawings, forming a part thereof.

Figure 1 is a perspective view of the boot, showing my new design;

Figure 2 is a plan view; and

Figures 3 and 4 are side elevational and front elevational views respectively.

The essential features of my design are shown in full lines.

I claim:

The ornamental design for a boot, substantially as shown and described.

OTIS G. MURTY.
